EXEMPLARY CLAIM

1. A compound of the formula

wherein Q is an atom in its highest oxidation state, said atom being selected from the class consisting of carbon and phosphorus, R_f is selected from the class consisting of fluorine and perfluoroalkyl radicals, m is 1-5 and n is zero to 2; and when Q is carbon and n is zero, R_f is perfluoroalkyl and includes Q.

2. Trifluoromethyl peroxyfluoride having the formula

3 Claims, No Drawings

FLUOROXIDANTS

This invention relates to certain fluorinated oxidant compounds and more particularly to certain novel peroxyfluorides.

The compounds of the invention are not, so far as applicant is aware, related to any class of heretofore known compounds.

The compounds of the invention are oxidizing agents and are useful for the purpose of bleaching, organic synthesis and the like. They are especially advantageous in that they have unique compatibility with systems in which perfluorinated solvents are used or perfluorinated compounds are treated. The compounds, when of lower molecular weight, as, for example, containing alkyl radicals having from one to four carbon atoms, are gases; when the alkyl radicals contained in the compounds are of higher molecular weight, the compounds are liquids. They are soluble in fluorinated compounds, such as chlorofluorocarbons (including CFCl_3 and CF_2Cl_2); fluorocarbons (including C_8F_{18} and perfluorobenzene) etc.

The compounds of the invention contain the moiety

joined to the remainder of the compound through an atom of the group consisting of carbon, sulfur and phosphorus, the said atom being in its highest valence state; and the remainder of the compound consisting of a non-metallic radical which is free from groups which are reducing in the respect to the $-\text{OOF}$ group and when carbon is present, at least one substituent fluorine atom is attached thereto. More specifically, and illustrative of a group of preferred compounds, the compounds can be represented by the formula

wherein Q is an atom in its highest oxidation state, said atom being selected from the group consisting of carbon, sulfur and phosphorus, R_f is selected from the group consisting of fluorine and perfluoroalkyl radicals, m is 0-5 and n is 0-2.

Exemplary compounds of the invention are:

It is noted that compounds containing two or more $-\text{OOF}$ groups can also be prepared.

In the examples set forth above, R_f can be a perfluoroalkyl radical having up to about 18 carbon atoms. Fully equivalent with acyclic fluoroalkyl radicals for

the purpose of the invention are perfluoroalkyl radicals containing perfluorinated carbocyclic and heterocyclic rings, for example, perfluoropyridyl, perfluorocyclohexyl, perfluorocyclohexylethyl and the like radicals. Likewise, the perfluoroalkyl radicals can be substituted by certain electronegative groups, which may replace one or more fluorine atom or CF_3 groups. They are characterized by being free from hydrogen and having a Hammett meta sigma parameter equal to or greater than 0.3. (reference is here made to the report of H. H. Jaffe, Chemical Reviews, Vol 53, pp. 191-261, 1953). Such groups include oxidizing groups such as $-\text{NF}_2$, $-\text{NF}$, $-\text{NO}_2$, chlorine, bromine and the like groups. These substituents do not interfere with the fluorination of the starting compound, and contribute significant additional oxidizing power to the compounds of the invention. Perfluoroalkyl radicals thus substituted are included within the scope of R_f as above defined.

The compounds of the invention can be prepared in general by the reaction of an acid, an acid anhydride, or a salt of an acid or a peroxide with fluorine or a fluoroxy compound. In many cases the acid salt is preferred over the acid or the anhydride.

Salts which can be employed in the fluorination process are, for example, the alkali metal salts, other metal salts, or ammonium salts of polyhaloalkanoic acids, which are exemplified by the acids having the formulae:

wherein X is a member of the group consisting of chlorine and fluorine; Z is a perhalomethyl radical having a total atomic weight not greater than 146.5; R_f is a perfluoroalkyl radical having from one to eight carbon atoms; n is an integer from 1 to 12; and m is a number from 0 to 5.

Other salts which may be employed are those of such acids as

Acid anhydrides which may be employed in reactions with fluoroxy compounds are

Suitable peroxides for use in the preparation of the compounds include

Fluoroxy compounds which are useful in the invention include oxygen difluoride (OF_2), dioxygen difluoride (O_2F_2), trioxygen difluoride (O_3F_2), and the like.

The reactions of the acids, salts, anhydrides or peroxides with fluorine or with fluoroxy compounds are best carried out at temperatures of from -150° C. to about 100° C. Temperatures below about 30° C. are preferred. It will be understood that reactions are not carried out at temperatures at which a starting material or product is markedly unstable. Free-radical initiation methods such as heat, ultraviolet radiation, or microwave radiation are needed for the reactions. Rapid quench of the reaction products in cold traps is desirable in many cases. When both reagents are gaseous they may be mixed and allowed to react. When one reagent is solid, the gaseous reagent is passed slowly over the solid to bring about reaction. Inert solvents or liquid suspension media may be employed but are not necessary. The procedures employed are illustrated in the examples.

EXAMPLE 1

The sodium salt of trifluoroacetic acid is fluorinated by a static bed procedure in a brass rectangular-shaped box reactor having a sintered monel plate suspended across it. The vessel is equipped with a gas inlet tube below the sintered plate and a gas outlet tube and brass blow-out cap above it. A 2.1 g. sample of sodium trifluoroacetate (about 15.6 millimoles) is spread out on the sintered plate in the fluorinating vessel. The reactor is flushed with nitrogen, fluorine is introduced into the nitrogen stream, and the mixture is passed into the vessel. The effluent stream is passed through an iron tube containing sodium fluoride at room temperature to remove hydrogen fluoride (which is present in commercial fluorine) and then through a trap immersed in liquid air. A stream of about 4 percent (by volume) of fluorine in nitrogen is passed through the reactor at a flow rate of 0.01 cubic ft./min. for 15 minutes, then a 20 percent stream at a flow rate of 0.007 cubic ft./min. for 1 hour, and finally a 34 percent stream at a flow rate of 0.004 cubic ft./min. for 2 hours. During this 3½ hour reaction period a total of 0.30 moles of fluorine is introduced into the reactor; the temperature inside the reactor varies from 17°–22° C. The fluorine flow is discontinued and the reaction vessel is then purged with nitrogen for one-half hour. The residual material in the reactor is found to weigh about 0.6 g.; it consists principally of NaHF_2 and NaF. An alternative method of preparing the peroxyfluorides is to introduce fluorine gas slowly into a pressure vessel containing either salts of oxalic acid or salts of perfluoroalkylcarboxylic acids.

The non-condensable gases are removed from the trap at liquid nitrogen temperature under reduced pressure. The liquid air trap is found to contain 9.3 millimoles of condensed products, including per-

fluoromethyl peroxyfluoride and perfluoroethyl peroxyfluoride. This material is isolated in pure form from the mixture by means of vapor phase chromatography. For this process a column 8 feet 7 inches in length and one-half inch in diameter packed with perfluorotributylamine (33 percent) coated on 30-60 mesh acid-washed filter aid(diatomaceous earth) (67 percent) and maintained at about -30° C . was used. An 8-volt thermistor was used as the detector. Helium was employed as the carrier gas at a flow rate of 130 ml./min. The pure products are obtained by passing the stream from the chromatograph exit through cooled traps as the respective components elute. The component eluting with a retention time of approximately 350 relative to CF_3OF under identical chromatography conditions is trifluoromethyl peroxyfluoride.

The F^{19} nuclear magnetic resonance spectrum of trifluoromethyl peroxyfluoride contains two absorptions, one at -291.5ϕ is due to the OOF group and the other at 69.2ϕ due to the CF_3 group. The -291.5ϕ peak is split into a quartet by the CF_3 group and the $+69.2 \phi$ peak is split into a doublet by the single F atom of the OOF group. The relative area ratio for the 69.2ϕ peak to -291.5ϕ is 3:1. The value of the coupling constant, J , is 4.5 cycles/sec.

The infrared spectrum of this material shows the following absorptions: $7.72\mu(s)$, $7.90\mu(s)$, $8.43\mu(s)$, $10.6\mu(m)$ and $13.18\mu(m)$. The relative intensities of the absorptions are indicated by the symbols S and M standing for strong and medium, respectively.

Elemental analysis of CF_3OOF gave the values 10.0 percent carbon and 61.8 percent fluorine. The molecular weight found was 122. Calculated for this compound are 10.0 percent carbon, 63.3 percent fluorine and a molecular weight of 120.

By irradiating a mixture of an excess of oxygen difluoride and $\text{FS(O}_2\text{)OOS(O}_2\text{)F}$, at room temperature with ultraviolet light, there is formed $\text{FS(O}_2\text{)OOF}$. The 40 product, fluorosylfuryl peroxyfluoride, boils at about 0° C.

EXAMPLE 2

The compound $\text{CF}_3\text{CF}_2\text{OOF}$ was also isolated from the products of the fluorination of salts of trifluoroacetic acid by vapor phase chromatography at -30°C . with perfluoroacetic acid by vapor phase chromatography at -30°C . with perfluorotributylamine as the stationary phase. The infrared spectrum of $\text{C}_2\text{F}_5\text{OOF}$ shows strong similarities to the spectra of $\text{C}_2\text{F}_5\text{OF}$ and CF_3OOF .

The F^{19} nuclear magnetic resonance spectrum of C_2F_5OOF shows an absorption at -291.6ϕ , assigned to the OOF group, at 84.1ϕ (the CF_3 group), and at 97.4ϕ (the CF_2 group). The absorptions at 84.1ϕ and 97.4ϕ are consistent for CF_3 and CF_2 , respectively, in a C_2F_5 group adjacent to an oxygen atom as observed in CF_3CF_2OF (82.1 ϕ and 97.9 ϕ , respectively). The relative area ratios of these absorptions are 1:3:2, respectively. The absorption of the OOF group is split into a triplet by the CF_2 group and a quadruplet by the CF_3 group. The absorption of the CF_2 group is split into a doublet by the single fluorine of the OOF group and into a quadruplet by the CF_3 group. The absorption of the CF_3 group is split into a triplet by the CF_2 and a doublet by the OOF, which are superimposed into a fourfold peak.

Analysis of the compound gave 14.1 percent carbon and 68.1 percent fluorine. Calculated values are 14.1 and 67.1 percent, respectively.

No decomposition was observed with a sample of C_2F_5OOF and $CFCl_3$ (n.m.r. internal reference) sealed in a glass tube after several weeks at ambient temperatures.

What is claimed is:

1. A compound of the formula

wherein Q is an atom in its highest oxidation state, said

atom being selected from the class consisting of carbon and phosphorus, R_f is selected from the class consisting of fluorine and perfluoroalkyl radicals, m is 1-5 and n is zero to 2; and when Q is carbon and n is zero, R_f is perfluoroalkyl and includes Q.

2. Trifluoromethyl peroxyfluoride having the formula

10

3. Perfluoroethyl peroxyfluoride having the formula
